US00D916043S

(12) **United States Design Patent** (10) **Patent No.:** **US D916,043 S**
(45) **Date of Patent:** **** Apr. 13, 2021**

(54) **MOBILE PHONE**

(71) Applicant: **Guangdong Oppo Mobile Telecommunications Corp., Ltd.,**
Guangdong (CN)

(72) Inventor: **Lisi Xu**, Guangdong (CN)

(73) Assignee: **GUANGDONG OPPO MOBILE TELECOMMUNICATIONS CORP., LTD.**, Dongguan (CN)

(**) Term: **15 Years**

(21) Appl. No.: **29/667,089**

(22) Filed: **Oct. 18, 2018**

(30) **Foreign Application Priority Data**

May 29, 2018 (CN) 201830260559.7

(51) LOC (13) Cl. **14-03**

(52) U.S. Cl.

USPC ..... **D14/138 G**

Primary Examiner — Jeffrey D Asch

(57) **CLAIM**

The ornamental design for a mobile phone, as shown and described.

DESCRIPTION

FIG. 1 is a rear, right perspective view of a mobile phone showing our new design;

FIG. 2 is a front view thereof;

FIG. 3 is a rear view thereof;

FIG. 4 is a left side thereof;

FIG. 5 is a right side thereof;

FIG. 6 is a top plan view thereof; and,

FIG. 7 is a bottom plan view thereof.

The shade lines in the figures show contour and not surface ornamentation.

The oblique shade lines in the figures show transparency or translucency.

1 Claim, 5 Drawing Sheets
